METHOD OF FRACTIONAL DISTILLATION

Ellsworth Watt, Augusta, Kans., assignor to
Socony-Vacuum Oil Company, Incorporated,
New York, N. Y., a corporation of New York

Application August 17, 1935, Serial No. 36,624

3 Claims. (Cl. 196—94)

This invention is directed to improvements in operations of fractional distillation of crude petroleum and/or similar products wherein vapors comprising petroleum products having a wide 5 boiling range are introduced to the mid-point of a bubble tower for fractionation therein into a bubble tower overhead product having a certain defined boiling range and a bubble tower bottom product having a defined boiling range, which is 10 heavier than that of the overhead product, and in which one or more side streams are taken from the bubble tower at points intermediate the tower top and the point of feed, and these side streams being finished in side stream stripping towers to 15 products having boiling ranges which are intermediate with respect to those of the bubble tower overhead product and bubble tower bottom product.

It is well known that in a regularly operating 20 bubble tower, wherein the stream of vapor passing up the column is reasonably regular in quality and constant in amount, and the stream of reflux oil passing down the column is also reasonably regular in quantity and constant in amount, that 25 the liquid on any one plate remains reasonably constant in quality. It is accordingly well known that if intermediate products are desired, that is products with a boiling range intermediate those of the bubble tower top product, and bubble tower 30 bottom product, that some plate may be found within the tower where the plate liquid approaches the quality of the desired intermediate product, and that a portion of this plate liquid may be withdrawn and finished to such intermediate product. It is with processes of this nature, that this invention is concerned.

More particularly, this invention is concerned with the production of solvent naphthas and the like of boiling ranges intermediate those of gasoline 40 and kerosene, such as for instance the product commonly known as varnish makers' and painters' naphtha, which is a naphtha used in the cleaning industry and for diluent and solvent in paint manufacture and the like, having an initial 45 boiling point of approximately 200° F. and an end boiling point of approximately 300° F. In the ordinary manufacture of these solvent naphthas, a side stream is taken from that portion of a tower fractionating vapors produced 50 from crude oil to produce a gasoline overhead at a point above the point where kerosene is withdrawn. That is to say, if the tower is one to which mixed vapors of kerosene and gasoline as produced from the crude oil and fed to be fractionated therein to a gasoline overhead product and a kerosene bottoms product, the solvent naphthas will be taken off as a side stream at 55 some point between the vapor entrance and the top of the tower. If, as in the more usual case, 60 the entire distillation and fractionation of the

crude is performed in a single tower, the gasoline being taken off as an overhead product and kerosene, gas oil, lube distillates and the like are taken as side stream products, the point of withdrawal of the solvent naphthas will be above the 5 point of withdrawal of the kerosene side stream.

The point selected for the withdrawal of these side streams is that plate, the liquid on which has an end point the same as that of the desired side stream. For instance, in the making of the 10 painters' naphtha mentioned above, the side stream would be withdrawn from a plate whereon the liquid has an end point of approximately 300°. These side stream towers are normally so connected that liquid for a particular side tower 15 may be withdrawn from any one of several of such plates. The point of withdrawal is the only manner in which the end distillation point of the side stream may be controlled. It frequently occurs that the liquid on a plate having the proper 20 end point is quite narrow in distillation range and not sufficiently rich in lighter fractions to meet the specifications required in the desired side stream. If sufficient light ends may be gotten in by refining streams from the several side 25 plates tapped for withdrawal to the side stream stripping tower, this method may be used. On some solvents, the distillation range is quite wide, the amount of light products being required 30 being sufficient to reduce the initial boiling point of 35 the side product to nearly that of the overhead product. In the production of such solvents, it is not normally possible to obtain these products by the manner of withdrawal of side streams, and fractionation by multiple towers must be 40 resorted to.

It is the object of this invention to provide a process whereby the distillation characteristics of the side stream may be so controlled as to yield a product of any desired end point, and of 45 initial boiling point and distillation characteristics in its lighter fractions approaching those of the overhead product; that is to say, it is an object of this invention to provide a process wherein complete control of the distillation characteristics of a side stream produced from a fractionating tower may be had regardless of the composition of the material originally withdrawn from the tower.

In order that this invention may be adequately 50 understood, reference is now made to the drawing attached to and made a part of this specification. The single figure of this drawing sets forth in diagrammatical form a distillation apparatus so equipped as to render it capable of the 55 process of this invention. In this drawing, I designate a fractionating column to which vapors for fractionation are fed through line 2, overhead product being withdrawn through line 3, condensed in condenser 4, and collected in receiver 60

5. From receiver 5 overhead product is withdrawn to storage through line 6, uncondensed gases, if any, are separately disposed of through line 7 and reflux is withdrawn through line 8 to be returned by pump 9 through line 10 for the control of the end distillation point of the overhead product by control of the temperature of tower 1. Tower bottoms products are removed to cooling and storage through line 11. Steam for assistance in the fractionation operation may be fed in through line 12 if desired. In the upper portion of this tower each of several trays designated 13 are provided with valved draw-off lines, which are manifolded together into line 14, which leads to a side stream stripping tower 15. Stripped side stream product is withdrawn to cooling and storage through line 16. The side stream stripping tower 15 is supplied with steam as desired through line 17, and steam and stripped vapors from side stream stripping tower 15 may be returned to the main fractionating tower through line 18. In addition to these elements, I have provided line 19 whereby a portion of the condensed overhead product of the main tower 20 may be returned to the top of the side stream stripping tower.

As an example of the operation of this fractionating system, we may consider an operation wherein the stripped product from the side stream stripping tower is the painters' naphtha above referred to, having for example a distillation range as follows:

Varnish makers' and painters' naphtha

	Degrees Fahrenheit
I. B. P.	200
10 per cent	228
20 per cent	237
30 per cent	243
40	255
40 per cent	262
50 per cent	267
60 per cent	273
70 per cent	278
80 per cent	285
90 per cent	312
E. P.	

It will very likely be found in this particular case that the stream from a single one of the plates 13 or the combined stream from two or more of these plates will enable the production of this desired side product. It may be assumed now that the quantity requirements for varnish makers' and painters' naphtha have been filled, and that it is desired to alter the operation of the fractionating system to produce as a side product a rubber solvent having the following distillation characteristics:

Rubber solvent

	Degrees Fahrenheit
I. B. P.	110
10 per cent	165
20 per cent	185
30 per cent	195
40	205
40 per cent	215
50 per cent	225
60 per cent	236
70 per cent	250
80 per cent	270
90 per cent	305
E. P.	

It will be noted that this product has practically the same end point as the product previously made, but that approximately 50% of it

is much lighter than the previous product, as the rubber solvent has an initial boiling point of 110° F. and a 50% point of 215° F., while the varnish makers' and painters' naphtha has an initial boiling point of 200° F. It is entirely unlikely that the withdrawal of product from the same location in the main tower will enable the production of this solvent, unless the over-all operation of the main tower is sufficiently changed to bring about the concentration of liquid of the proper characteristics upon the plates which are tapped to permit the withdrawal of side streams. These solvent products are made in amounts which are usually relatively quite small in proportion to the total capacity of operation of the main distillation unit. Economical operation of the main distillation unit requires that it be adjusted to produce the products which are mainly required, and alteration of the preceding operation to bring about concentration of the desired liquid, for the production of rubber solvents on the plates 13 may well require adjustments which will entirely unbalance the unit for the economical production of the products mainly required. For this purpose I have provided line 19 whereby a portion of the condensed overhead product from the main tower, which is much lighter than any liquid which may be collected on the plates 13, may be returned to the top of the side stream stripping column 15. By selection of the proper plate 13, by regulation of the amount drawn through line 14, by regulation of the amount of condensed main tower overhead returned through line 19 and by regulation of the amount of steam introduced through line 17, each with respect to the others, I may so adjust the nature of the total feed to side stream stripping tower 15 and the nature of the fractionation operation performed therein as to permit me to produce a product of any desired distillation characteristics without deranging or in any way changing the operation of the main fractionating tower 1 from the manner in which it operated while producing desired major products in an economical manner.

It will be seen from the above discussion that I have thus provided a means whereby the distillation range of a side stream product from a fractionating tower may be controlled irrespective of the nature of the liquid withdrawn from the main tower, except as to end point. The many applications of this process of control of side product will be apparent to those acquainted with the art.

I claim:

1. The method of fractional distillation capable of controlling the distillation range of a side stream product from a fractionating tower which comprises the steps of withdrawing side stream of desired end point from a fractionating tower, introducing that stream into a side stream stripping tower, introducing into the feed level of the same side stream stripping tower a portion of condensed overhead product from the main fractionator and steam distilling the combined liquids in said side stream stripping tower, the proportions of side stream withdrawn, of condensed overhead fed to the stripping tower, and the amount of steam fed thereto, being adjusted with respect to each other to produce as a side stream product a fraction having an end point substantially the same as that of the side stream originally withdrawn and a distillation range

with respect to lighter proportions intermediate that of the side stream originally withdrawn, and the main tower overhead product.

2. That method of operating a side stream stripping tower which comprises the steps of introducing into the side stream stripping tower to flow therethrough in admixture with the feed a portion of product from the main fractionating tower having boiling range lighter than the side stream originally withdrawn, and controlling the distillation in said side stream stripping tower to make a product of boiling range intermediate that of the side stream originally withdrawn, and that of the condensed main tower product added to the side stream stripping tower.

3. That process of fractional distillation which comprises the steps of introducing a vapor to a main fractionating tower to be fractionated therein into an overhead product and a bottoms

product, condensing the overhead product and returning a portion of it to the main fractionator tower for control thereof, withdrawing a portion of the reflux in the main fractionating tower at a point intermediate its ends, introducing the 5 portion of reflux so withdrawn into a second fractionating column to be contacted with steam therein, and introducing a portion of condensed main tower overhead product to the feed level of the same secondary fractionating tower, to 10 flow therethrough in admixture with the intermediate reflux stream and likewise to be contacted with steam therein, and withdrawing from the bottom of the secondary fractionating tower a liquid product of the controlled distillation 15 range which is intermediate that of the side stream originally withdrawn and that of the main tower overhead product.
